UNITED STATES PATENT OFFICE.

HENRY G. BRANDWEIN, OF CHICAGO, ILLINOIS.

MATTRESS.

Application filed November 21, 1921. Serial No. 516,822.

My invention relates to improvements in mattresses, and more particularly to a mattress, cushion, or other similar article, so made that the tufting shall be confined entirely within the interior of the body of the mattress.

Another object of my invention is to provide a mattress of the kind described which shall be non-stretchable in either its length or width, or both, as desired.

The invention has among its further objects the production of a mattress of the kind described which is simple, compact, durable, reliable, sanitary and satisfactory for use wherever found applicable.

Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts,

Fig. 1 is a plan view of my device, showing a portion of the top cover sheet broken away;

Fig. 2 is a section taken substantially on the line 2—2 of Fig. 1;

Fig. 3 is a section taken substantially on the line 3—3 of Fig. 1;

Fig. 4 is a section similar to that shown in Fig. 2, but illustrating a modified form, and

Fig. 5 is a section taken substantially on the line 5—5 of Fig. 4.

In the drawings, wherein I have illustrated the preferred embodiments of my invention, there is shown a pair of opposed cover sheets 1 and 2, as shown, one of these being the bottom sheet and the other the top sheet. The bounding edges of said sheets have binding or side portions 3 secured thereto to connect the spaced cover sheets and secure them together to provide a receptacle, so that a filling material 4, of hair, felt, cotton, or any other suitable fiber or filling may be stuffed therein to make a resilient cushion. The corners or edges of the mattress may be stitched or formed so as to provide roll edges about each face of the mattress.

Ordinarily mattresses are made by stuffing

the filling material between the opposed cover sheets and then tufting said filled mattress at regular or irregular intervals. The ordinary process of tufting is to pass 60 threads of twine, rope, or other suitable material, through both sheets of the mattress and secure the outer ends of said tufts by tying to leather, felt, or like washers, to prevent the twine or thread from tearing 65 through the cover sheets. Dirt, dust or other foreign matter usually gathers under these washers, making the mattress unsightly and unsanitary. These washers or tufts often become lost, and when weight is on 70 the mattress, the same may hang loose when the ties slacken up, and perhaps pull out.

In order to overcome this objectionable manner of tufting, I provide in one form narrow bands or strips of material 5, of 75 either cloth, tape, twine, rope, or the like, and secure the same to the inner surface of one of the cover sheets, as for instance, the cover sheet 2 (see Fig. 2), preferably in parallel rows. At regular intervals along 80 the length of the strip, the material is formed with depending loops 6, the free ends of said loops being secured to the inner surface of the opposed cover sheet 1, as shown. In this manner there is provided a double 85 thickness of the strip 5 at the tuft, and a single thickness between the tufts.

In order to more securely fasten the ends of the tufting against pulling out and to make a stronger mattress, the opposite ends 90 of the tufting strips are extended in opposite directions, as for instance the end 7 of the strip secured to the inner surface of the sheet 2 extends to the left, while the other end 8 extends to the right, to form substantially a Z-shaped tufting strip. This is not essential to the construction. The strips 5 are secured to the sheets in the preferred construction by rows of stitching 9, and, if desired, other rows of stitching 10 may be 100 passed through the sheets transversely of the rows 9, passing through the ends of the tufting strips in the row; or, in other words, the rows of stitching 9 and 10 may extend both lengthwise and crosswise of the mattress and intersect at the ends of the tufting strips. These rows of stitching reinforce the mattress against stretching, and therefore tend to keep it in shape so that the tufting 6 cannot pull out.

The strips 5 are sewed in place with the tufting 6 secured to both sheets before the

filling material 4 is inserted into the mattress. In case the filling material is of hair or the like, it is forced between the sheets, and then the open end of the mattress closed. In case the filling material is of cotton, felt, or the like, sections of said filling material, substantially equal in width to the distance between parallel rows of tufting, are inserted by means of a guide, if so desired, between said parallel rows of tufting, and then the mattress is pounded or otherwise manipulated to force said filling material around the tufting to securely hold said material against displacement.

In the modification or simplified form shown in Figs. 4 and 5, the strip portions intermediate the tufting 6 have been omitted, the tufting in this modification each comprising a strip of material 11 having its ends 12 and 13 extending in opposite directions to form substantially a Z-shape, and secured at said oppositely-extending ends to the inner surfaces of the cover sheets 1 and 2. The stitching 9 and 10, or either of them, may be employed, if so preferred.

Thus it is seen that, as described, there is provided a mattress, cushion, pillow, or the like, having a tufted effect and appearance, and in which the tufting strips are confined entirely within the interior of the body thereof. Not only is the mattress more pleasing in appearance and more sanitary than the mattress with tufting projecting beyond the exterior sides of the cover sheets, but the reinforcing stitching and strips, if employed, extending either lengthwise or crosswise of the mattress, or in both directions, makes the mattress practically non-stretchable.

Having thus described my invention, it is obvious that various immaterial modifications may be made in the same without de-

parting from the spirit of my invention; hence I do not wish to be understood as limiting myself to the exact form, construction, arrangement and combination of parts herein shown and described, or uses mentioned.

What I claim as new and desire to secure by Letters Patent is:

1. A mattress of the kind described, comprising a pair of superimposed sheets, filling material therebetween, and a narrow strip of material extending along the inner surface of one of said covers and adapted to contact with and be secured at spaced intervals to the inner surface of the other cover to form tufting therebetween.

2. A mattress of the kind described, comprising a pair of superimposed spaced sheets, filling material therebetween, and a narrow strip of material bent upon itself at intervals to form a plurality of loops and secured to the inside surface of one of said covers between said loops so as to have the loops extending therefrom, said loops secured at their free ends to the inner surface of the other cover to form tufting between said covers.

3. A mattress of the kind described, comprising a pair of superimposed spaced sheets, filling material therebetween, and a narrow strip of material bent upon itself at intervals to form a plurality of spaced loops and secured to the inside surface of one of said covers between said loops so as to have the loops extending therefrom at spaced intervals, the free ends of said loops bent to extend oppositely to the other end and secured at said bent free ends to the inner surface of the other cover to form tufting between said covers.

In testimony whereof, I have hereunto signed my name.

HENRY G. BRANDWEIN.
